US00D489975S

(12) United States Design Patent (10) Patent No.: US D489,975 S
(45) Date of Patent: * May 18, 2004

(54) FOOD PACKAGE

(75) Inventors: Daniel C. Jackson, Plymouth, MN (US); Nicolas Bouveret, St-Placide (CA); Jean-Pierre Lacroix, Bois d'Amont (FR)

(73) Assignee: Land O'Lakes, Inc., Arden Hills, MN (US)

() Term: 14 Years

(21) Appl. No.: 29/165,907

(22) Filed: Aug. 20, 2002

(51) LOC (7) Cl. 09-03

(52) U.S. Cl. D9/425

(58) Field of Search D9/414, 424, 425, D9/426, 428, 429, 341; D7/619, 602, 641; 229/400, 406, 407, 938, 902, 903, 905, 906, 116.1, 108; 220/4.21, 4.27, 556, 669-675, 656-659; 426/106; 256/505, 515

(57) CLAIM

The ornamental design for a food package, as shown and described.

DESCRIPTION

FIG. 1 is a perspective view of an embodiment of the food package of the present invention;

FIG. 2 is a top plan view of the embodiment;

FIG. 3 is a front elevational view of the embodiment;

FIG. 4 is a right side elevational view of the embodiment;

FIG. 5 is a left elevational view of the embodiment;

FIG. 6 is a rear side elevational view of the embodiment;

FIG. 7 is a bottom plan view of the embodiment;

FIG. 8 is a perspective view of a second embodiment of the food package of the present invention;

FIG. 9 is a top plan view of the second embodiment;

FIG. 10 is a front elevational view of the second embodiment;

FIG. 11 is a right side elevational view of the second embodiment;

FIG. 12 is a left elevational view of the second embodiment;

FIG. 13 is a rear side elevational view of the second embodiment;

FIG. 14 is a bottom plan view of the second embodiment;

FIG. 15 is a perspective view of a third embodiment of the food package of the present invention;

FIG. 16 is a top plan view of the third embodiment;

FIG. 17 is a front elevational view of the third embodiment;

FIG. 18 is a right side elevational view of the third embodiment;

FIG. 19 is a left elevational view of the third embodiment;

FIG. 20 is a rear side elevational view of the third embodiment; and,

FIG. 21 is a bottom plan view of the third embodiment.
